United States Patent Office

Des. 179,589
Patented Jan. 29, 1957

179,589

PRESSURE REDUCING REGULATOR

Evans R. Billington, Chicago, Ill., assignor to The Bastian-Blessing Company, Chicago, Ill., a corporation of Illinois

Application September 14, 1954, Serial No. 32,272

Term of patent 14 years

(Cl. D78—1)

Fig. 1

Fig. 2

Fig. 3

Fig. 4

Fig. 1 is a top plan view of a pressure reducing regulator showing my new design;

Fig. 2 is an end elevational view thereof, the opposite end thereof being substantially the same;

Fig. 3 is a bottom view thereof; and

Fig. 4 is a side elevational view thereof, the opposite side being substantially the same.

I claim:

The ornamental design for a pressure reducing regulator, as shown and described.
